UNITED STATES PATENT OFFICE.

FREDERICK W. HUENNEKENS, OF MILWAUKEE, WISCONSIN.

DESIGN FOR A WASHER.

SPECIFICATION forming part of Design No. 28,511, dated April 26, 1898.

Application filed October 27, 1897. Serial No. 656,584. Term of patent 3½ years.

To all whom it may concern:

Be it known that I, FREDERICK W. HUENNEKENS, a citizen of the United States, residing at Milwaukee, county of Milwaukee, and State 5 of Wisconsin, have invented and produced a new and original Design for a Washer, of which the following is a specification, reference being had to the accompanying drawings, forming part thereof.

10 Figure 1 is a plain view of a washer, showing my new design. Fig. 2 is a sectional view.

As shown in the drawings, the leading or material feature of my design consists of a

washer with a hole in the center and a concentric slot, as shown in Fig. 1.

It is apparent that this design is applicable to ball-retaining washers with oil-hole, in bicycle-hubs, and other similar articles.

Having described my invention, what I claim as new, and desire to secure by Letters Patent, is—

The design for a washer, as herein shown and described.

FREDERICK W. HUENNEKENS.
